NUMBERING HEAD

Filed Oct. 28, 1922

UNITED STATES PATENT OFFICE.

AMOS H. SMITH, OF BROOKLYN, NEW YORK, ASSIGNOR TO AMERICAN BANK NOTE COMPANY, OF NEW YORK, N. Y., A CORPORATION OF NEW YORK.

NUMBERING HEAD.

Application filed October 28, 1922. Serial No. 597,442.

To all whom it may concern:

Be it known that I, Amos H. Smith, a citizen of the United States, residing at the borough of Brooklyn, in the city of New York, county of Kings, and State of New York, have invented certain new and useful Improvements in Numbering Heads, of which the following is a specification, reference being had therein to the accompanying 10 drawings, which form a part thereof.

My invention relates to numbering heads, and more particularly to numbering heads of the type in which the digit wheels are progressively actuated by means of a comb 15 pawl.

Heretofore in this type of numbering head, it has been the common practice to actuate the swing frame carrying the comb pawl by means of a depressible plunger 20 adapted to engage the blanket of the impression cylinder and be depressed against the tension of springs acting on said plunger as a result of this engagement. The downward movement of said plunger sets the 25 pawl, so that immediately upon leaving the impression cylinder, the springs operative upon the plunger will restore it to its normal position, and, in so doing, will actuate the swing frame and the comb pawl carried 30 thereby in a manner to turn the digit wheel or digit wheels which with any particular set of the machine are required to be turned with that actuation thereof.

The old and well known construction 35 above referred to has the disadvantages that the actuation of the digit wheels is solely under spring power, the springs themselves being subjected to frequent and rapid compressions so that they were often broken and defective work produced causing a waste 40 of material and labor; that the inking rollers had to be cut away so as to prevent the actuation of the numbering head as a result of the engagement of the plunger therewith; that wear upon the impression cylinder 45 blanket was excessive at the point of engagement between same and the plungers and the various numbering heads; and that the numbering heads could not be so set as to prevent the progressive actuation of

the digit wheels in case it were desired to repeat any number or group of numbers.

In a machine embodying my invention the swing frame is actuated by a member which is at all times positioned below the printing 55 plane of the characters upon the digit wheels, and is adapted to be actuated by a striker operative thereon between the point of engagement of the digit wheels with the impression cylinder and the inking mechanism, engagement of said striker with said actuating member resulting in a positive turning movement of one or more digit 60 wheels according to the set of the head. By thus utilizing a positive movement in actuating the digit wheels, the return movement of said actuating member may be under the control of a spring of fairly light tension, since no work beyond the resetting 65 of the swing frame and its comb pawl is required upon the return movement of the actuating member.

The actuating member is so constructed as to minimize the speed at which the digit wheel or wheels are turned, although the 70 movement under all circumstances is rapid, a condition present in all progressively actuated numbering heads.

I also provide the numbering head embodying my invention with means operative 75 upon the actuating member whereby said member may be moved and maintained out of the operative relation to the striker, thus permitting a continued actuation of the numbering machine using the head, without 80 progressive actuation of the digit wheel.

If desired, a locking pawl may be used upon each wheel of a denomination higher than the units wheel, so as to prevent the turning of any digit wheel except when the 90 digit wheel of next lower denomination has the digit 9 in the printing position.

The invention consists primarily in a numbering head embodying therein a main frame, a fixed shaft therein, a sequence of 95 independently rotatable digit wheels mounted upon said shaft, a ratchet wheel carried by each of said digit wheels, the ratchet wheels of the digit wheels of lower denomination having a recess therein, a swing 100

frame mounted in said main frame, a comb pawl carried by said swing frame, the teeth of which are of graduated decreasing heights from the units digit wheel toward 5 the wheels of successively higher denomination, actuating means operative upon said swing frame including therein an oscillatory member positioned in its entirety below the printing plane of the characters 10 upon said digit wheels, operative connections between same and said swing frame, and a spring acting thereon, the teeth upon said ratchet wheel co-operating with a pawl being so set as to cause movement of the 15 wheel co-operating therewith with movement of said member against the tension of said spring and to cause the pawl to ride upon said teeth with the actuation of said member by said spring; and in such other 20 novel features of construction and combination of parts as are hereinafter set forth and described, and more particularly pointed out in the claims hereto appended.

Referring to the drawings,

25 Fig. 1 is a plan view of a numbering head embodying my invention;

Fig. 2 is a side view thereof from the right of Fig. 1;

Fig. 3 is a section on the line 3—3 of Fig. 30 1;

Fig. 4 is a section on the line 4—4 of Fig. 1;

Fig. 5 is an end view showing the setting 35 means for the digit wheel actuating mechanism; and

Fig. 6 is a detail view of one of the digit wheels illustrating the locking mechanism therefor.

Like letters refer to like parts throughout 40 out the several views.

In the embodiment of my invention shown in the drawings, the main frame of the machine a is provided with side plates a' and a'' extending between which is a shaft b having idly mounted thereon a plurality of 45 digit wheels c, c', c'', c^3, c^4 and c^5 rotatable independently one of the other. It is a common practice in numbering heads of this character to also provide character wheels 50 which are not actuated by the mechanisms actuating some of the digit wheels, but are nevertheless rotatable in order to permit the use of the different characters thereon, or 55 different groupings of such characters in the event that a plurality of such wheels are used. The character wheels are indicated at $d—d'$ respectively.

Each of the wheels c to c^5 and $d—d'$ is 60 provided upon one side thereof with a ratchet wheel permanently secured thereto in any desired manner so as to be rotatable therewith, the ratchet wheels upon the respective digit and character wheels being indicated at $e, e', e'', e^3, e^4, e^5, e^6$ and e^7 . These ratchet 65 wheels are adapted to be engaged by pawls

forming a part of the actuating mechanism for progressively turning those digit wheels which are adapted to be mechanically actuated and are also adapted to be engaged by spring-pressed detent pawls $f, f', f^2, f^3, f^4, f^5, f^6$ and f^7 with the two fold object of resisting the rotative movement of the various wheels when actuated by the actuating mechanism, or when setting the wheels by hand, to prevent overrunning of the wheels during such movement, and in the event of a slight excess or insufficient movement thereof, to impart slight movement thereto in which ever direction may be necessary to ensure proper alinement of the various digits or characters. This general arrangement and combination of parts is old and well known in this art, but is referred to merely as being characteristic of the type of numbering head to which my invention relates.

Idly mounted upon the shaft d is a swing frame g , the opposite arms of which are positioned between the end plates a' — a'' respectively and the units digit wheel c and the character wheel d' . Pivoted in this swing frame and spring-pressed towards the various ratchet wheels, is a comb pawl g' of the usual construction, which includes a sequence of teeth, the first of which is adapted to engage the ratchet wheel connected with the units digit wheel, and the rest of which are of graduated, decreasing heights so as to be inoperative with relation to the ratchet teeth upon the succeeding digit wheels except when a transfer operation is required with regard to the particular wheel with which each tooth is adapted to co-operate.

Each ratchet wheel has a recess as e^8 adjacent one of the teeth, which is adapted to be engaged by the co-operating tooth of the comb pawl, when the digit g is in the printing position so as to permit the pawl to move towards the shaft and bring other teeth thereof into engagement with the ratchet wheel of the adjacent digit wheel or wheels.

One hub of the swing frame g has formed thereon a segmental gear h in constant mesh with a segmental gear i carried by a shaft j pivoted in the side frame a' . This shaft j has keyed or otherwise secured thereto a crank arm k having an impact member k' , preferably an antifriction roller, adapted to engage a striker member forming a part of the numbering machine upon which the numbering head is adapted to be mounted. This crank arm is acted upon by a spring m of light tension which normally thrusts it towards the top of the end plate a' until the operative relation of the gears h and i will have the effect of limiting the movement of the crank and its shaft under the control of said spring in a position where the crank k and the impact member k' car-

ried thereby will be positioned below the printing plane of the characters upon the various wheels, and thus be in a position where under no circumstances can it engage 5 the impression cylinder, and the inking rollers, of the numbering machine.

The teeth of the various ratchet wheels are so set that when the swing frame *g* is 10 in the position shown in the several views of the drawings with the crank *k* in the uppermost position, the comb pawl will engage a tooth of at least one of the ratchet wheels so that upon the next actuation of the crank *k*, the digit wheel carrying the 15 ratchet thus engaged will receive a one-tenth revolution while power is being applied directly to said crank arm by the striker member, and while said spring is restoring said crank *k* to its normal position 20 to impart a return oscillatory movement to the swing frame *g*, said pawl will ride idly over the succeeding tooth of said ratchet wheel and come into a position engaging same preparatory to the next feeding movement. 25 In this manner a positive actuation of the various digit wheels is assured and the sole function of the spring *m* is a restoring action, thus permitting uniformity in the action of said spring irrespective of 30 the number of digit wheels which are to be turned with the actuation of the swing frame. As a result, a spring *m* of light tension may be used.

Under some conditions it is desirable to 35 use numbering heads without progressively actuating the digit wheels, to permit which I provide means whereby after the crank *k* has once been actuated, or after it has been depressed manually, it may be held in this 40 position so that the spring *m* cannot restore it and the swing frame *g* and its appurtenances to a position where the striker of the numbering machine can operatively effect said mechanisms. This means in the form 45 of the invention shown, consists of a lever *n* pivotally mounted at one end of the side plate *a'* having thereon a bolt *o* adapted to enter a socket *p* formed in the perimeter of the segmental gear *i*.

50 In numbering heads of the type in which the digit wheels are actuated by a comb pawl, there is always a tendency of adjacent digit wheels to adhere together as a result of accumulation and drying of ink between 55 same, to correct which condition I have heretofore produced heads of this type in which each digit wheel is positively locked against rotation until the wheel of next lower denomination has the digit 9 in the printing 60 position.

In a numbering head embodying my present invention, I combine with the other characteristics of the mechanism, such a locking means, although per se this locking means is 65 old in this art. It may, however, be ad-

vantageous to combine it with the other characteristics of the numbering head, and when it is so combined it imparts desirable characteristics to the head, particularly as with a slow actuating movement of the 70 comb pawl under positive power, the likelihood of the accidental turning of digit wheels is greater than with the quick "snap" action of springs, which latter would have a greater tendency to break an ink bond than 75 would the slower movement resulting from the actuating mechanism employed in my present construction of numbering head.

The locking mechanism shown in the accompanying drawings consists of a sequence 80 of sockets *q* formed in the perimeter of all digit wheels above the units digit wheel and between the characters thereon, and a co-operating lever *q'* associated with each digit wheel and having an angular head adapted 85 to enter such sockets respectively. These levers are pivoted on a fixed shaft *r* adjacent the bottom of the head and each lever is acted upon by a spring, indicated at *q''*, and has a short arm or heel *q''* operatively 90 engaging a cam shaft *s*. An actuating handle *s'* is secured to the shaft *s* for imparting a turning movement thereto so that all of the locking levers may if desired, be simultaneously disengaged from the digit 95 wheels with which they respectively co-operate, to permit the hand setting of the various digit wheels.

Each of the digit wheels, excepting the 100 last of the sequence, and including the units wheel, has on one face thereof, opposite to that to which the ratchet wheel is secured, a cam groove indicated at *t* in Fig. 6, which groove is positioned outside the ratchet wheel of the adjacent wheel, and has a 105 single rise and fall *t'* so located that it will be in its operative position when the digit 9 of the wheel having the cam groove therein is in the printing position. Each locking lever *q'* is provided with a thin bracket *u* entering the space between the peripheries of adjacent digit wheels and carrying a small stud *u'* entering the cam groove *t* of the wheel of next lower denomination. 110

The operation of the herein described numbering head is substantially as follows:—

Ordinarily a plurality of groups of numbering heads, as herein described, are 120 mounted upon the numbering head cylinder of a numbering machine, such machines being so constructed as to permit adjustment of such heads circumferentially as well as longitudinally of said cylinder. It is because of this frequent adjustment of heads 125 that the location of the crank *k* and its impact member *k'* below the printing plane of the characters upon the various digit wheels and in a position where they cannot 130

engage the impression cylinder and the inking rollers, is of primary importance. When the above conditions exist, adjustment of the numbering heads will not require new inking rollers, and all portions of the blanket of the impression cylinder will be in a condition to permit the desired printing pressure at any point of the impression cylinder due to the fact that some portions of the blanket are not subjected to greater wear than other portions due to frequent impact with a plunger for the purpose of actuating the head.

In starting a run of the machine, after the completion of the preparatory inking of the characters of the digit wheels of lower denomination, the various digit wheels upon the numbering heads are set by hand, the locking mechanism when used being released to permit this hand setting of the machine.

When preparing for a run, the numbering heads of each circumferential group will ordinarily be set differently, the setting of the different groups of heads also being different according to the number of impressions to be made on each sheet and the contemplated length of a run.

During the operation of the machine, the functioning of each numbering head will be identical with that of every other, so that the detailed operation of but one head will be described. The printing characters upon each digit wheel are first inked and then brought into printing relation to the impression cylinder. After an impression has been made, the continued rotation of the cylinder carrying the head brings the impact member k' into engagement with a striker member on the machine so as to oscillate the crank k against the tension of the spring m and cause the intermeshing gears h and i to actuate the swing frame g in one direction. Assuming that the first impression by the units wheel is of the digit 1, this movement of the swing frame will cause the tooth of the pawl g' engaging the ratchet wheel f to impart a one-tenth revolution to the digit wheel c as a result of, and during the engagement between, the impact member k' and the striker member not shown in the drawings. Immediately, however, that the impact member k' moves out of engagement with said striker member, the spring m will impart a return movement to the crank k and, through the gears h and i and the shaft j , to the swing frame g , the comb pawl g' during such return oscillation of the swing frame as a result of the action of said spring, riding idly over the next tooth of the ratchet wheel e , but having no operative effect upon the digit wheel c .

Upon the completion of this return movement of the swing frame g and its pawl g' ,

the tooth of said pawl cooperating with the ratchet wheel e will engage the succeeding tooth, so that the operation above described will be repeated upon the succeeding revolution of the numbering head. This actuation of the units wheel occurs with each revolution of the numbering head, the actuation of a digit wheel of higher denomination occurring only when all wheels of lower denomination have the digit 9 in the printing position. For example, when the digit 9 of the wheel c is in the printing position, the highest tooth of the comb pawl g' will drop into the recess e' of the units digit wheel ratchet wheel, thus permitting the next higher tooth to engage the ratchet e' of the tens wheel. During the next revolution of the numbering head, since one tooth of the comb pawl engages one of the teeth of the ratchet wheel e' , and another tooth engages one of the teeth of the ratchet wheel e , the movement of the swing frame as a result of the depression of the crank k will turn both wheels simultaneously one-tenth of a revolution in the manner above described. When both the units and tens wheels have the digit 9 in the printing position, the adjacent tooth will be brought into engagement with the ratchet wheel e^2 , this relation being extended progressively to all wheels of higher denomination which are adapted to be actuated by the comb pawl. All wheels not directly engaged by a tooth of the comb pawl remain idle.

Owing to the fact that the number of sheets printed during a run of the numbering head during a day is never great, it is the common practice to provide for the automatic actuation of but four or five of the digit wheels, it being feasible to set the hundred thousandth wheel, and sometimes the ten thousandth wheel, by hand.

Whenever the digit 9 comes to the printing position, the rise t' of the cam t formed in said wheel will, through the stud u' and bracket u , disengage the locking lever q' from the wheel of next higher denomination, thus permitting the free rotation of this wheel upon the next actuation of the numbering head, said locking lever or pawl immediately reengaging the socket q of its wheel upon the completion of a one-tenth revolution thereof so as to positively hold said wheel against rotation until said lever has again been actuated by said cam. It will be understood that, as in all locking mechanisms of this type, the locking means may be disengaged from a digit wheel without likelihood of the accidental turning of said wheel so long as the locking mechanism operative upon a digit wheel, between the digit wheel thus released, and the units digit wheel, is set.

The arrangement of the gears h and i will

cause them to lock in a manner to check return reciprocatory movement of the crank k under the control of the spring m in a manner to limit the upward movement of 5 said crank and keep it below the printing plane of the digit wheels.

Since the various detent pawls f to f^7 will have the usual function in securing alignment of the digit wheels of the numbering 10 head, a detailed description thereof is therefore unnecessary.

If it be desired to prevent the automatic actuation of any of the digit wheels, it is merely necessary to depress the crank k and 15 engage the bolt o with the socket p in the gear i , thus holding the impact member k' out of the operative relation to the striker member of the numbering machine, and preventing a return movement of the crank k 20 under the control of the spring m , and a resultant return movement of the swing frame. It is apparent that no exactitude is required in the relation of the bolt o and the socket p , since if these parts prevent a full 25 return movement of the crank k , slight oscillatory movement may be imparted thereto by the striker without having any operative effect upon the digit wheels.

While the wheels $d-d'$ are not subject 30 to change during the operation of the head, I preferably extend the locking mechanism to these disks as well as the detent pawl mechanism, since the accidental operation of these disks is to be avoided and structural uniformity throughout the head is desirable.

Since the crank k acts at long leverage 35 upon the shaft j , it is apparent that the movement of the swing frame g will be very much slower than though strong springs were used, and that the slowing down of the 40 movement of the digit wheels will have a very strong tendency to minimize likelihood of overrunning of the wheels. Furthermore, by this positive operation of the swing frame and the actuating mechanism therefor, likelihood of a failure of the actuating 45 mechanism to function is practically eliminated, and thus inconveniences resulting from the accidental breakage of springs in heads as heretofore used, is obviated.

Since the spring m always has the same 50 load, irrespective of the number of digit wheels which are to be turned, this spring may be made of fairly light tension, particularly as it has little work to do. All 55 digit wheels will be actuated under exactly the same conditions irrespective of the number of wheels to be turned, since the power for turning these wheels is derived from the main source of power of the numbering machine and not from the energy of a 60 spring or springs carried by the numbering head itself.

It is not my intention to limit the invention to the precise details of construc-

tion shown in the accompanying drawings, it being apparent that such may be varied without departing from the spirit and scope of the invention.

Having described the invention, what I 70 claim as new and desire to have protected by Letters Patent, is:—

1. A numbering head embodying therein a main frame, a fixed shaft therein, a sequence of independently rotatable digit wheels mounted upon said shaft, a ratchet wheel carried by each of said digit wheels the ratchet wheels of the digit wheels of lower denomination having a recess therein, a swing frame mounted in said main frame, 80 a comb pawl carried by said swing frame, the teeth of which are of graduated decreasing heights from the units digit wheel toward the wheels of successively higher denomination, actuating means operative upon said swing frame including therein an oscillatory member positioned in its entirety below the printing plane of the characters upon said digit wheels, operative connections between same and said swing frame, 85 and a spring acting thereon, the teeth upon said ratchet wheel co-operating with a pawl being so set as to cause movement of the wheel co-operating therewith with movement of said member against the tension of 90 said spring and to cause the pawl to ride upon said teeth with the actuation of said member by said spring.

2. A numbering head embodying therein a main frame, a fixed shaft therein, a sequence of independently rotatable digit wheels mounted upon said shaft, a ratchet wheel carried by each of said digit wheels, the ratchet wheels of the digit wheels of lower denomination having a recess therein, a swing frame mounted in said main frame, 100 a comb pawl carried by said swing frame, the teeth of which are of graduated decreasing heights from the units digit wheel toward the wheels of successively higher denomination, actuating means operative upon said swing frame including therein an oscillatory member positioned in its entirety below the printing plane of the characters upon said digit wheels, a shaft carrying said oscillatory member, intermeshing segmental gears carried by said shaft and said swing frame respectively, and a spring acting upon said oscillatory member, the teeth upon said 105 ratchet wheel co-operating with a pawl being so set as to cause movement of the wheel co-operating therewith with movement of said member against the tension of said spring and to cause the pawl to ride upon said teeth with the actuation of said member by said spring.

3. A numbering head embodying therein a main frame, a fixed shaft therein, a sequence of independently rotatable digit wheels mounted upon said shaft, a ratchet wheel 110

carried by each of said digit wheels, the ratchet wheels of the digit wheels of lower denomination having a recess therein, a swing frame mounted in said main frame, a 5 comb pawl carried by said swing frame, the teeth of which are of graduated decreasing heights from the units digit wheel toward the wheels of successively higher denomination, actuating means operative upon said 10 swing frame including therein an oscillatory member positioned in its entirety below the printing plane of the characters upon said digit wheels, operative connections between same and said swing frame, a 15 spring acting thereon, the teeth upon said ratchet wheel co-operating with a pawl being so set as to cause movement of the wheel co-operating therewith with movement of said member against the tension of said 20 spring and to cause the pawl to ride upon said teeth with the actuation of said member by said spring, and means whereby said oscillatory member may be held against movement under the control of said spring.

25 4. A numbering head embodying therein a main frame, a fixed shaft therein, a sequence of independently rotatable digit wheels mounted upon said shaft, a ratchet wheel carried by each of said digit wheels, the ratchet wheels of the digit wheels of lower denomination having a recess therein, a swing frame mounted in said main frame, a comb pawl carried by said swing frame, the teeth of which are of graduated 30 decreasing heights from the units digit wheel toward the wheels of successively higher denomination, actuating means operative upon said swing frame including therein an oscillatory member positioned in its entirety below the printing plane of the characters upon said digit wheels, a shaft carrying said oscillatory member, intermeshing segmental gears carried by said shaft and said swing frame respectively, a spring acting upon said oscillatory member, the teeth upon said ratchet wheel co-operating with a pawl being so set as to cause movement of the wheel co-operating therewith with movement of said member against the tension of said 35 spring and to cause the pawl to ride upon said teeth with the actuation of said member by said spring, and means whereby said oscillatory member may be held against movement under the control of said spring.

40 5. A numbering head embodying therein a main frame, a fixed shaft therein, a sequence of independently rotatable digit wheels mounted upon said shaft, a ratchet wheel carried by each of said digit wheels, the ratchet wheels of the digit wheels of lower denomination having a recess therein, a swing frame mounted in said main frame, a comb pawl carried by said swing frame, the teeth of which are of graduated 45 decreasing heights from the units digit wheel toward the wheels of successively higher denomination, actuating means operative upon said swing frame including therein an oscillatory member positioned in its entirety below the printing plane of the characters upon said digit wheels, operative connections between same and said swing frame, and a spring acting thereon, the teeth upon said ratchet wheel co-operating with a pawl being so set as to cause movement of the wheel co-operating therewith with movement of said member against the tension of said 50 spring and to cause the pawl to ride upon said teeth with the actuation of said member by said spring, and means whereby said oscillatory member may be held against movement under the control of said spring.

55 6. A numbering head embodying therein a main frame, a fixed shaft therein, a sequence of independently rotatable digit wheels mounted upon said shaft, a ratchet wheel carried by each of said digit wheels, the ratchet wheels of the digit wheels of lower denomination having a recess therein, a swing frame mounted in said main frame, a comb pawl carried by said swing frame, the teeth of which are of graduated 60 decreasing heights from the units digit wheel toward the wheels of successively higher denomination, actuating means operative upon said swing frame including therein an oscillatory member positioned in its entirety below the printing plane of the characters upon said digit wheels, operative connections between same and said swing frame, and a spring acting thereon, the teeth upon said ratchet wheel co-operating with a pawl being so set as to cause movement of the wheel co-operating therewith with movement of said member against the tension of said 65 spring and to cause the pawl to ride upon said teeth with the actuation of said member by said spring.

wheel toward the wheels of successively higher denomination, actuating means operative upon said swing frame including therein an oscillatory member positioned in its entirety below the printing plane of the characters upon said digit wheels, a shaft carrying said oscillatory member, intermeshing segmental gears carried by said shaft and said swing frame respectively, a spring acting upon said oscillatory member, the teeth upon said ratchet wheel co-operating with a pawl being so set as to cause movement of the wheel co-operating therewith with movement of said member against the tension of said spring and to cause the pawl to ride upon said teeth with the actuation of said member by said spring, the segmental gear carried by the shaft to which said oscillatory member is attached having a socket therein, and a lever pivotally connected with the frame of the machine and having a bolt adapted to enter said socket when said member is depressed, whereby a return movement of said member under the control of said spring is prevented.

6. A numbering head embodying therein a main frame, a fixed shaft therein, a sequence of independently rotatable digit wheels mounted upon said shaft, a locking member operative upon each wheel of a denomination higher than the units wheel, co-operating members carried by each of said locking members and the wheel of next lower denomination than that upon which it is operative, whereby when the digit 9 of said wheel of lower denomination is in the printing position, said locking member will be disengaged from its digit wheel, a ratchet wheel carried by each of said digit wheels, the ratchet wheels of the digit wheels of lower denomination having a recess therein, a swing frame mounted in said main frame, a comb pawl carried by said swing frame, the teeth of which are of graduated decreasing heights from the units digit wheel toward the wheels of successively higher denomination, actuating means operative upon said swing frame including therein an oscillatory member positioned in its entirety below the printing plane of the characters upon said digit wheels, operative connections between same and said swing frame, and a spring acting thereon, the teeth upon said ratchet wheel co-operating with a pawl being so set as to cause movement of the wheel co-operating therewith with movement of said member against the tension of said spring and to cause the pawl to ride upon said teeth with the actuation of said member by said spring.

7. A numbering head embodying therein a main frame, a fixed shaft therein, a sequence of independently rotatable digit wheels mounted upon said shaft, a locking member operative upon each wheel of a de-

nomination higher than the units wheel, co-operating members carried by each of said locking members and the wheel of next lower denomination than that upon which it is operative, whereby when the digit 9 of said wheel of lower denomination is in the printing position, said locking member will be disengaged from its digit wheel, manually operative means whereby all of said locking members may be simultaneously made inoperative with relation to their respective digit wheels to permit hand setting of said wheels, a ratchet wheel carried by each of said digit wheels, the ratchet wheels of the digit wheels of lower denomination having a recess therein, a swing frame mounted in said main frame, a comb pawl carried by said swing frame, the teeth of which are of graduated decreasing heights from the units digit wheel toward the wheels of successively higher denomination, actuating means operative upon said swing frame including therein an oscillatory member positioned in its entirety below the printing plane of the characters upon said digit wheels, operative connections between same and said swing frame, and a spring acting thereon, the teeth upon said ratchet wheel co-operating with a pawl being so set as to cause movement of the wheel co-operating therewith with movement of said member against the tension of said spring and to cause the pawl to ride upon said teeth with the actuation of said member by said spring.

8. A numbering head embodying therein a main frame, a fixed shaft therein, a sequence of independently rotatable digit wheels mounted upon said shaft, a locking member operative upon each wheel of a denomination higher than the units wheel, co-operating members carried by each of said locking members and the wheel of next lower denomination than that upon which it is operative, whereby when the digit 9 of said wheel of lower denomination is in the printing position, said locking member will be disengaged from its digit wheel, manually operative means whereby all of said locking members may be simultaneously made inoperative with relation to their respective digit wheels to permit hand setting of said wheels, a ratchet wheel carried by each of said digit wheels, the ratchet wheels of the digit wheels of lower denomination having a recess therein, a swing frame mounted in said main frame, a comb pawl carried by said swing frame, the teeth of which are of graduated decreasing heights from the units digit wheel toward the wheels of successively higher denomination, actuating means operative upon said swing frame including therein an oscillatory member positioned in its entirety below the printing plane of the characters upon said digit wheels, operative connections between same and said swing frame, and a spring acting thereon, the teeth upon said ratchet wheel co-operating with a pawl being so set as to cause movement of the wheel co-operating therewith with movement of said member against the tension of said spring and to cause the pawl to ride upon said teeth with the actuation of said member by said spring.

9. A numbering head embodying therein a main frame, a fixed shaft therein, a sequence of independently rotatable digit wheels mounted upon said shaft, a ratchet wheel carried by each of said digit wheels, the ratchet wheels of the digit wheels of lower denomination having a recess therein, detent pawls operative upon said ratchet wheels respectively, a swing frame mounted in said main frame, a comb pawl carried by said swing frame, the teeth of which are of graduated decreasing heights from the units digit wheel toward the wheels of successively higher denomination, actuating means operative upon said swing frame including therein an oscillatory member positioned in its entirety below the printing plane of the characters upon said digit wheels, operative connections between same and said swing frame, and a spring acting thereon, the teeth of which are of graduated decreasing heights from the units digit wheel toward the wheels of successively higher denomination, actuating means operative upon said swing frame including therein an oscillatory member positioned in its entirety below the printing plane of the characters upon said digit wheels, operative connections between same and said swing frame, and a spring acting thereon, the teeth upon said ratchet wheel co-operating with a pawl being so set as to cause movement of the wheel co-operating therewith with movement of said member against the tension of said spring and to cause the pawl to ride upon said teeth with the actuation of said member by said spring.

10. A numbering head embodying therein a main frame, a fixed shaft therein, a sequence of independently rotatable digit wheels mounted upon said shaft, a locking member operative upon each wheel of a denomination higher than the units wheel, co-operating members carried by each of said locking members and the wheel of next lower denomination than that upon which it is operative, whereby when the digit 9 of said wheel of lower denomination is in the printing position, said locking member will be disengaged from its digit wheel, manually operative means whereby all of said locking members may be simultaneously made inoperative with relation to their respective digit wheels to permit hand setting of said wheels, a ratchet wheel carried by each of said digit wheels, the ratchet wheels of the digit wheels of lower denomination having a recess therein, detent pawls operative upon said ratchet wheels respectively, a swing frame mounted in said main frame, a comb pawl carried by said swing frame, the teeth of which are of graduated decreasing heights from the units digit wheel toward the wheels of successively higher denomination, actuating means operative upon said swing frame including therein an oscillatory member positioned in its entirety below the printing plane of the characters upon said digit wheels, operative connections between same and said swing frame, and a spring acting thereon, the teeth of which are of graduated decreasing heights from the units digit wheel toward the wheels of successively higher denomination, actuating means operative upon said swing frame including therein an oscillatory member positioned in its entirety below the printing plane of the characters upon said digit wheels, operative connections between same and said swing frame, and a spring acting thereon, the teeth upon said ratchet wheel co-operating with a pawl being so set as to cause movement of the wheel co-operating therewith with movement of said member against the tension of said spring and to cause the pawl to ride upon said teeth with the actuation of said member by said spring.

tion, actuating means operative upon said swing frame including therein an oscillatory member positioned in its entirety below the printing plane of the characters upon said 5 digit wheels, operative connections between same and said swing frame, a spring acting thereon, the teeth upon said ratchet wheel co-operating with a pawl being so set as to cause movement of the wheel cooperating therewith with movement of said member 10 against the tension of said spring and to cause the pawl to ride upon said teeth with

the actuation of said member by said spring, and means whereby said oscillatory member may be held against movement under the 15 control of said spring.

In witness whereof I have hereunto affixed my signature, in the presence of two subscribing witnesses, this 9th day of October 1922.

AMOS H. SMITH.
